UNITED STATES PATENT OFFICE.

WALTER E. DILLARD, OF PETERSBURG, VIRGINIA.

BELT-SHIFTER.

No. 825,265.

Specification of Letters Patent.

Patented July 3, 1906.

Application filed February 20, 1905. Serial No. 246,564.

To all whom it may concern:

Be it known that I, WALTER E. DILLARD, a citizen of the United States, residing at Petersburg, in the county of Dinwiddie and State of Virginia, have invented a new and useful Belt-Shifter, of which the following is a specification.

This invention relates to belt-shifting mechanism, and has for its principal object 10 to provide a shifting and starting mechanism that will dispense with the usual loose pulley and avoid all unnecessary wear on the belt.

A further object of the invention is to provide a device of this character in which the 15 starting may be accomplished without friction or undue strain on the driving-belt; and a further and important object of the invention is to provide means whereby a dead belt may be started into motion in advance of its 20 shifting to a tight pulley, so that the starting may be accomplished with little or no strain, thus reducing the wear and jar on the machinery as well as lengthening the life of the belt.

25 With these and other objects in view, as will more fully hereinafter appear, the invention consists in certain novel features of construction and arrangement of parts herein-after fully described, illustrated in the accompanying drawings, and particularly 30 pointed out in the appended claims, it being understood that various changes in the form, proportions, size, and minor details of the structure may be made without departing 35 from the spirit or sacrificing any of the advantages of the invention.

In the accompanying drawings, Figure 1 is 40 a side elevation of a belt-shifting mechanism constructed in accordance with the invention. Fig. 2 is a sectional elevation of the same. Fig. 3 is a detail view showing the belt-shifting mechanism. Fig. 4 is a plan view of the belt-shifting mechanism.

Similar characters of reference are employed to indicate corresponding parts 45 throughout the several figures of the drawings.

In the present invention the fast pulley A is secured to a line-shaft B, and at a point to one side of the pulley is arranged a second 50 smaller pulley or belt-wheel 10, also tight on the shaft. In some cases this second pulley will not be necessary, especially where the line-shaft is of large diameter and the driving-pulley A of comparatively small diameter.

Secured to the ceiling or other suitable

point is a frame 12, that is provided with a suitable opening for the passage of the shaft, the opening being of sufficient diameter to avoid frictional wear. This frame is provided with a plurality of radially-disposed slots 13, through which extend studs 14, having securing-nuts by which they may be locked in adjusted position, and on each of the studs is arranged a small roller 15, of 60 which the end rollers 15' may be provided with annular flanges 16. The construction is such that the frames may be made of a standard size, the radial slots permitting adjustment of the studs in order to employ the 65 shifting mechanism in connection with pulleys of different size.

Secured to the fixed frame is an eccentric 17, that is also provided with an opening for the passage of the shaft, the latter passing 75 freely through said opening, and on the eccentric is mounted an eccentric-strap 18. From the strap 18 extends an arm 19, that is provided with an elongated slot 20, extending in a direction radially from the center of 80 the eccentric 17. Adjustably secured in this slot is a stud 21, which extends loosely through a slot 23, that is formed in an arcuate line concentric with the center of the eccentric 17. The stud supports a belt-tightening pulley 24, and said pulley may be moved from the dotted-line position to the full-line 85 position shown in Fig. 1 by a downward pull on a cord or chain 25 or any suitable means for transmitting movement to the lever 19. 90

Around the several pulleys passes a belt 26, that preferably is of a width at least equal to the width of the belt to be shifted, and under normal conditions this belt is loose on the pulleys or rollers, assuming the dotted-line 95 position shown in Fig. 1, so that when the driving-belt is transferred it will form a simple yieldable cushion on which the driving-belt may rest without injury.

When the driving-belt is to be transferred 100 to the tight pulley, the lever 19 is moved upward and the belt 26 is tightened, a portion of the length being brought into contact with the smaller pulley 10 or with the periphery of the shaft, as the case may be, whereupon 105 movement is imparted from the line-shaft to the belt 26, and this movement is gradually imparted to the driving-belt, so that the latter is set into motion in advance of its transfer to the pulley A. It will be seen that 110 when the lever 19 is pulled down the eccentric is lowered and the belt 26 is then

moved away from the belt-wheel 10, so that there will be no wear on the belt even though the wheel continues to revolve.

At a point adjacent to the belt and in a position either over or under the same is a transversely-extending arm 28, carrying a standard or bracket 29 of any suitable construction. Pivoted to this bracket are the inner ends of spindles 30, that extend in planes oblique to the length of the belt. These spindles carry antifriction-rollers 31, arranged to engage with the face of the belt, and for this purpose the outer end of each spindle is connected to a suitably-guided cord or chain 32, the lower end of which is arranged within convenient reach of the operator. When the belt is in motion, one or other of the cords or chains 32 is operated and the corresponding spindle is raised until the roller 31, carried thereby, engages the face of the belt, and as said roller is disposed obliquely to the length of the belt the latter will be gradually moved in a lateral direction and shifted from the belt-rest to the fast pulley, or vice versa. There is no wear then on the edge of the belt such as occurs with ordinary shifting-forks which engage only with the edge of the belt. In the present instance the shifting might be accomplished by a simple direct vertical movement of the roller as a whole, but it is found that by gradually altering the angular position of the roller with respect to the horizontal that the belt will ride off more readily to the point where it is to be shifted; but it is only after the belt has been completely moved that the roller engages with the edge of said belt, as will be apparent on reference to Fig. 3. When the operator releases the cord or chain 32, the shifting-roller will move by gravity to a position out of contact with the belt, thus avoiding unnecessary wear.

It is obvious that the eccentric 17 is not essential in all cases, but its use is deemed advisable, owing to the greater surface of the belt which may be guided into contact with the periphery of the lower pulley through which motion is transmitted to said belt. The eccentric causes belt-carrying pulley 24 to move upward in a curved path which gradually approaches the periphery of the small driving-pulley 10, and thus tightens the belt around a greater portion of the periphery of said pulley than would be the case if the pulley 24 moved in a path concentric with the

periphery of the pulley 10. Furthermore, on the downward movement of the eccentric the belt is lowered away from the periphery of the pulley 10 to a greater distance than would be possible if said pulley 24 traveled in a path concentric with the periphery of the pulley 10.

Having thus described the invention, what is claimed is—

1. In a device of the class specified, a shaft, a pulley and a belt-wheel mounted thereon, a supporting-belt arranged for the reception of a driving-belt, a plurality of idlers around which the supporting-belt passes, and means for forcing the belt into engagement with the pulley whereby movement from the latter is transmitted to the supporting-belt, and from thence to the driving-belt.

2. In a device of the class specified, the combination with a frame, of a plurality of rollers carried thereby, a line-shaft including a driving member, an eccentric, an eccentric-strap surrounding the same, a lever on the strap, a tightening-roller carried by the lever, and a belt passing around the several rollers and driving member.

3. In a device of the class specified, the combination with a frame, of a series of rollers supported thereby, one or more of said rollers being flanged, a line-shaft, a driving-pulley on the line-shaft, a belt extending loosely around the driving-pulley and the rollers, an eccentric, an eccentric-strap surrounding the same, a lever connected to the eccentric-strap, and a belt-tightening roller carried by said lever.

4. In a device of the class specified, the combination with a frame having a plurality of radial slots, of rollers having studs adjustable in said slots, a driving-pulley, an eccentric, an eccentric-strap, a lever mounted on the eccentric-strap and having a longitudinally-arranged slot, the frame being provided with an arcuate slot struck from the center of the eccentric, a stud extending through the two slots, a belt-tightening pulley on said stud, and a belt surrounding the pulleys and rollers.

In testimony that I claim the foregoing as my own I have hereto affixed my signature in the presence of two witnesses.

WALTER E. DILLARD.
